METHOD FOR MANUFACTURING POTTERY
WARE

William J. Miller, Swissvale, Pa.

Original application July 14, 1933, Serial No.
680,483. Divided and this application May 6,
1935, Serial No. 19,990

13 Claims. (Cl. 25—156)

This invention relates to the manufacture of high quality table pottery ware, such as plates, cups and saucers and more particularly to improved methods and means for segregating charges of clay from a mass, preshaping blanks therefrom and applying, securing and shaping the blanks on absorbent molds for subsequent jiggering to final finish and polish.

This application is a division of my co-pending application for United States Letters Patent S. No. 680,483, filed July 14, 1933, for Method of and apparatus for the manufacture of potteryware.

The objects are to reduce manual labor required; insure continuity of production; reduce clay wastage and the percentage of defective ware; improve the quality and quantity of the ware produced and generally reduce production costs.

The method contemplates the steps of supplying at convenient, and if desired, irregular intervals, semi-conditioned clay masses to a reserve hopper; progressing it into and through conditioning, column forming and progressing apparatus; measuring and severing predetermined length slugs therefrom each containing a multiple of charges, to provide a reserve supply; determining the slug length, instant of and frequency of slug production by the volume of clay withdrawn in the production of a multiple of charges; welding the slug ends together and smoothing the weld; successively severing portions from the slug and controlling the volume of each portion by the volume withdrawn in preceding charge forming operations; depositing the portions in a stabilizing reserve well; applying a substantial pressure to the clay in the well to amalgamate it with the residue therein and progress it through an orifice into a charge measuring chamber; measuring and forming a charge; limiting the volume progressed by the capacity of the chamber; establishing said capacity by positioning one wall of said chamber in predetermined position; maintaining a reserve supply in said well; controlling the supply of clay thereto by the volume of the reserve supply remaining in the well and by the volume of the preceding charge withdrawn; severing the charge at a predetermined point from its source of supply; transferring the charge to a forming station; forming the charge on all surfaces into a blank of predetermined shape and size closely approaching or bearing a distinct relation to the finished ware; determining the water content of each surface of the blank; holding the blank against a shaped permeable form by suction through the form

while transferring and applying the blank to the surface of an absorbent or permeable mold; applying and securing the blank in predetermined angular position and uniform concentric bulk distribution to the mold while held by said form; progressively spreading the blank over the mold from center to periphery by pressing it between the form, a stationary permeable matrix, and a movable absorbent and/or permeable mold until the brim is extended, the surface contoured and the thickness established to substantially coincide with that of the finished ware; repelling the shaped ware from the matrix and form by forcing air under pressure through the permeable walls of the matrix and form, and suction to the under side of the mold, substantially at the instant of recession of mold from matrix and form; transferring the mold and shaped ware to a finishing station; rotating the shaped ware surface secured to the mold against a profile tool to finally finish and polish the surface and brim, thereafter drying the ware while still on the mold.

In the drawings:

Figure 1 is a sectional elevation on line I—I, Fig. 2, showing the main parts of an apparatus embodying my invention;

Fig. 2 is a plan view of the apparatus;

Fig. 3 is a detail of a retarder for the feeder belt of the apparatus;

Fig. 4 is a section on line IV—IV, Fig. 2; and

Fig. 5 is an enlarged view of a portion of Fig. 1.

In Figs. 1, 4 and 5, I show a frame A with cross members B provided with a series of accurately spaced holes B₁ for dowels by which are secured to and positioned on the frame, a conditioning and extruding apparatus C, a slug measuring and segregating apparatus D, a clay supply reserve or stabilizing and compacting device E, a charge measuring apparatus F, a blank forming apparatus G, a blank applying and conforming apparatus H, a treating apparatus J, and a charge segregating, forming and conveying turret K, these several apparatus constituting one line of a contemplated multiple of parallel lines of production. Frame A also houses mold conveying apparatus L and mold and former operating apparatus M common to all lines of production.

Molds 1 positioned in seats 1_a on trays 2 are intermittently progressed along track 2_a by pawl 3 on lever 4 oscillated by cam 5 on drive shaft 6, to a position adjacent the apparatus H and M and thereafter to a synchronized automatic profiling apparatus (not shown). Mold 1 is lifted from seat 1_a against a matrix 12 by a chuck 7 adjustably secured to a crosshead 8, by means of

a toggle joint 9, 9a, operated through a link 10 by a cam 11. Semi-conditioned clay is fed into a hopper 13 and finally conditioned in the screw extruder C, then progressed through a die 14 as 5 a column by means of an electric motor 15 controlled by relay 16, contacts 17, 18 and anchor switch 19, said motor driving the screw of the extruder. When a belt 20 advances the column 21 a predetermined distance, cam 22 rotating in 10 unison with the belt 20 lifts the anchor 19 and operates a cutter 23 to part and release a slug of predetermined length from the tail 24 of the column in the die 14 and permit it to gravitate on rollers 25 towards, collide with and weld to the 15 preceding slug 27 (Fig. 5), the weld being smoothed when drawn between rollers 27a; further progression of belt 20 causes a pin 26 on cam 22 to shift the anchor 19 to right against the contact 18 to start the motor 15 and extrude 20 a fresh column of clay over rollers 25 until the end contacts with and shifts anchor 19 to left against adjustable contact 17 to stop motor 15 and extruder C.

Thus clay slugs are extruded, severed and 25 conveyed by measuring device D at the same rate as used by the reserve of stabilizing device E. The conditioning device C, slug forming device D, and stabilizing device E, together, provide a reserve clay supply to insure uninterrupted 30 operation. To control the intensity of impact between slugs 21 and 27, rollers 25 are connected with retarders, for example fluid pumps, Fig. 3, having the circulation restricted by a valve 28.

A crosshead 29 is reciprocated vertically on 35 guides 30 by cam 11 through link 10, crank 9a and link 9b and through bolts 31a carries a plate 31 which houses a bushing 32 in threaded engagement therewith. A housing 33 fixed to the frame A has a rectangular reserve well 34 in 40 which a ram 35 is reciprocated by the plate 31 through a stem 36, the adjustable bushing 32, nuts 37, and a spring 38. A bracket 39 secured to stem 36 loosely embraces and reciprocates a rack bar 41 which engages a gear 42 driving a 45 roller 43 through internal ratchet and pawl (not shown) to progress the belt 20 and slug 27 intermittently to left only. A spring 47 and nuts threaded on the bar 41 provide a resilient and adjustable stroke of the same.

50 As ram 35 descends it shears off protruding end of slug 27, and progresses the clay through a port 44 into a circular chamber 45 of the disk shaped turret K having teeth 46 for its rotation, until the chamber 45 is filled, then spring 38 55 yields, thus arresting descent of the ram 35 and rack 41; meantime, a pawl 40 on a stem 40a has locked the gear 42 to temporarily prevent advance of slug 27. Upon elevation of crosshead 29, the spring 47 is compressed leaving the 60 rack 41 stationary until at the end of the elevation of the bracket 39 it lifts the stem with the pawl 40. The spring 47 then advances slug 27 to the extent to which the ram 35 has descended, so that as less clay remains in the well, more 65 clay is deposited therein, and vice-versa. As ram 35 descends, a former 48 is elevated into the chamber 45 through a lever 49 and pitman 50 actuated from the plate 31, a predetermined distance adjustable while in operation through a 70 screw similar to screw 51, Fig. 4. The former determines the diameter, lower contour and bulk of the charge, and it enables the chambers 45 in the turret to be filled to less than capacity by any desired extent. After retraction of the 75 former 48, a one-way rack pawl 52 operated by

the lever 4 and pivoted to crossbar 53, engages the teeth 46 of turret K to turn in counter-clockwise by one division to shear the charge from the mass by the action of a grid 44a, and carry it to a preforming position G. A lock 54 operated by the pawl 52 at the termination of its travel locates and holds the turret 46 stationary, while an upper former 55, Fig. 4, and a lower former 56, advance into the chamber 45 to contour both surfaces of the blank 57, the degree of pressure applied being adjustable through nuts 58 and spring 59 on a pitman 59a. Replaceable bushings 57a facilitate substitution of various brim shape and diameter blank formation, and exchangeable liners 57b between the housing and its removable base 33a facilitate substitution of various length bushings, whereby the effective depth of the chamber may be varied.

Blank 57 is next brought under a final former 60 adapted to enter the chamber 45 when it reaches position H where the blank is transferred, conformed and secured to the surface of the mold I through matrix 12 and the former 60. Former 60 is reciprocated by the crosshead 29 through a hollow stem 60a which extends through a bushing 60b and is threaded and grooved for applying a nut 60c above, and a pressure relief collar 60d below the bushing 60b. Collar 60d houses a series of adjustable spring pressed balls 60e which seat in the groove of stem 60a. When excess pressure is applied they release, thus controlling maximum pressure application and also avoiding breakage. Bushing 60b serves to adjust the lowermost extent of travel of former 60 thereby determining the thickness of the central portion of the formed ware and the threaded stem of the chuck I determines the thickness of the brim portion of the formed ware by enabling the chuck to be vertically adjusted in the crosshead 8 which has an internally threaded opening receiving said stem. At position J, chamber 45 may be cleaned and treated to prepare it for a subsequent charge. Thereafter mold I is transferred to final finishing and polishing apparatus. The faces of the blank are preferably contoured 45 convex to facilitate spreading and to insure against entrapping air between the clay and the mold, avoid folds, etc.

The clay contacting faces of matrix 12, ram 35, formers 48, 60, 55, and 56 are of permeable material and their opposite faces are chambered and in communication with a source of sub- and super-atmospheric pressure, controlled by adjustable cam operated valves not shown, to control clay adhesion to and repulsion from these surfaces. During transfer of the blank from chamber 45 to mold I, sub-atmospheric pressure may be admitted through the face of former 60 to attract and hold the blank thereto, thus insuring proper blank placement. Also, by applying sub- or super-atmospheric pressure of predetermined pressure, the instant and duration of application to the clay through the permeable faces of formers 48, 55, 56, and 60, during and/or following the forming operation, the water content of each face of the blank may be predetermined prior to application to the mold.

Wheresoever the term "pressing" or derivatives shall occur in the appended claims with respect to the shaping of clay it shall mean the co-operation of co-extensive surfaces forming therebetween a cavity in which clay is subjected to forces in compression. Wheresoever in the appended claims the term "spreading" shall occur with respect to the application of clay to a mold, it

shall mean a radial flow of the clay in all directions simultaneously over the surface of the mold as by squeezing between relatively movable surfaces.

5 The formers are arranged to extract moisture from the clay by squeezing, or by the combined action of squeezing and suction, the extracted water entering the pores of the permeable clay contacting surface of the formers. This may 10 occur incident to any stage in the processing where the clay is operated upon by permeable formers with or without suction connections. By extracting water from the clay charge, the tendency toward plastic deformation is reduced, 15 particularly during transfer from one position to another when suspended by its brim. Obviously, the extraction of water will shorten the subsequent drying time required.

The blank brim is compacted against and defined and supported by the chamber wall to facilitate transportation and concentric application to the mold without distortion, thus insuring uniform radial spread and final concentric regular outlined brim in the formed ware, the large diameter and thin regular section also contributing towards said result. I thus dispense in the subsequent jiggering operation, with trimming off and discarding the irregular excess brim resulting from applying irregular compact unformed 30 charges, unguided, direct to the mold. The jiggering operation referred to is for the purpose of finishing and polishing the exposed surface of the shaped ware surface. Finishing or polishing in the art is the final step in the profiling operation accompanied by slurring the material to produce a smooth final finish and polish and the operation does not entail the removal of excess material.

While I have shown and described the preferred 40 embodiment of my invention, I wish it to be understood that I do not confine myself to the precise details of construction herein set forth, by way of illustration; it is apparent that many changes and variations may be made therein, 45 by those skilled in the art, without departing from the spirit of the invention, or exceeding the scope of the appended claims.

I claim:

1. In the manufacture of pottery ware, the 50 method of forming clay charges which consists in compacting clay from a source of supply into a closed chamber, determining the bulk of the charges by regulating the depth of the chamber, severing each successive charge from its source 55 of supply, and then shaping the charge to approximate ware shape independently of the mold on which the ware is finally finished.

2. In the manufacture of pottery ware, the 60 method which consists in extruding clay in the form of a column, severing the column into suitable lengths, successively severing portions adequate for the making of a plurality of ware pieces from the forward end of the lengths and compacting the portions so severed into a confined 65 mass, severing successive charges from the mass, shaping the charges, and transferring the charges to molds preparatory to shaping and finishing the charges into ware.

3. Method of making pottery ware comprising 70 segregating a measured charge of predetermined bulk from a mass of conditioned clay, moulding the charge on all surfaces into a blank having predetermined brim and faces and shape and size approaching those of the finished ware and 75 thereafter applying the blank to a mold.

4. A method according to claim 3 including the step of profiling to polish the same.

5. The method of manufacturing pottery ware which comprises, forming a body containing a multiple of mold charges, reducing the body to a plurality of individual charges of relatively thin substantially disk-like proportions, applying each charge centrally to a mold on which the ware is to be jiggered, pressing the charge to spread the same completely over the ware-forming surface 10 and to full ware diameter, and thereafter profiling the exposed surface thereof.

6. The method of fabricating pottery ware which comprises, forming a charge of clay on all surfaces into a blank having a predetermined 15 shape and size and regular outlined brim, applying the blank and securing it to a mold, pressing the blank thereagainst until the brim is extended to full diameter, the surface finally contoured and the thickness established to substantially coincide with that of the finished ware and thereafter subjecting the mold and ware to a drying atmosphere.

7. The method of fabricating dinnerware which comprises, forming a charge of clay into a blank 25 of predetermined shape and size, extracting fluid from the clay, applying the blank in predetermined angular position to a mold, pressing the blank on the mold to extend the brim and contour the surface of the blank, profiling the blank to finish and polish the surface and thereafter drying the clay whilst still retained on the mold.

8. The method of fabricating pottery ware which consists in, forming a clay blank having a predetermined shape and size, applying the blank 35 to a mold, pressing the blank between the mold and a stationary matrix to extend the brim to full ware diameter, repelling the clay from the matrix, jiggering the clay to finish and polish the same and thereafter drying the clay whilst still on the mold.

9. The method of fabricating pottery ware which consists in, forming an undersized clay blank, applying the blank in predetermined angular position to a mold and securing the same thereto, progressively spreading the blank over the mold from center to periphery by stationary permeable matrix until the brim is extended to full ware diameter, repelling the clay from the matrix by forcing air under pressure through the permeable walls of the matrix whilst applying suction to the under side of the mold substantially at the instant of recession of the mold from the matrix and thereafter finishing the exposed surface of the clay and drying the same 55 whilst retained on the mold.

10. The method of fabricating pottery ware which consists in, forming an undersized clay blank, transporting the blank whilst suspended by its brim to a position concentric with the ware forming surface of a mold, applying the blank to the mold and expanding the same, limiting the degree of expansion on the mold to the area of the ware forming surface of the mold, jiggering at least one surface of the clay and thereafter drying the same.

11. The method of fabricating pottery ware which consists in producing a clay charge having a minimum of surplus material and then molding this charge into a thin section blank, 70 applying the blank to a mold and expanding the blank to fully cover the ware forming surface of the mold whilst confining the blank thereto and thereafter drying the clay on the mold.

12. A method of making pottery ware which 75

consists in shaping a clay mass having a volume of material therein equal to one mold charge into a disc having definitely outlined brim and contoured faces, laying the disc on the ware forming surface of a mold, the disc occupying a position from whence it may be spread in all directions equi-distantly upon the application of an expanding force and thereafter pressing the clay to expand it to full ware diameter and cause it to flow over the ware forming surface of the mold and then jiggering the clay.

13. A method of manufacturing pottery ware

from plastic clay which consists in preshaping a body of clay by moulding into a charge having the material distributed therein in such a manner that when the body is deposited on the center of distribution of a mold and pressed between co-operating surfaces, it will flow equi-distantly over the exposed portion of mold and attain full ware diameter, depositing the charge of material on a mold and pressing it to expand the same as aforesaid and thereafter jiggering the mold bonded clay.
